VEHICLE WINDOW VENTILATOR OR SIMILAR ARTICLE

Herbert Buerger, Walton, N. Y.

Application April 14, 1950, Serial No. 9,205

Term of patent 14 years

(Cl. D14—6)

To all whom it may concern:

Be it known that I, Herbert Buerger, a citizen of the United States, residing at Walton, in the county of Delaware and State of New York, have invented a new, original, and ornamental Design for a Vehicle Window Ventilator or Similar Article, of which the following is a specification, reference being had to the accompanying drawing, forming part thereof.

In the drawing:

Fig. 1 is a front elevational view of the vehicle window ventilator, showing my new design;

Fig. 2 is a top plan view of the vehicle window ventilator, showing my new design.

Fig. 3 is a cross sectional view taken on line 3—3 of Fig. 1.

I claim:

The ornamental design for a vehicle window ventilator or similar article, as shown.

HERBERT BUERGER.
